George Dobson

By

Attorney S.

UNITED STATES PATENT OFFICE.

GEORGE DOBSON, OF SEGO, UTAH.

MINE DRILL.

Application filed August 19, 1921. Serial No. 493,687.

To all whom it may concern:

Be it known that I, GEORGE DOBSON, a citizen of the United States, residing at Sego, in the county of Emery, State of Utah, have invented certain new and useful Improvements in Mine Drills; and I do hereby declare the following to be a full, clear, and exact description of the invention, such as will enable others skilled in the art to which it appertains to make and use the same.

This invention relates to mine drills and it has for its object to provide a structure that will be extremely light so that it may be readily transported from one place of use to another and which may be readily shifted both vertically and horizontally to make cuts in a corresponding variety of directions from the support. A further object of the invention is to provide a structure in which the drill and its motor may be readily shifted bodily in a vertical direction and in which the mechanism in all of its various adjusted positions may be held securely in whatever of its adjusted positions the motor with its drill may be. Other objects and advantages of the invention will be understood from the following description.

In the drawings:

Figure 1 is a side elevation showing a drill embodying the present invention set up in position for use.

Figure 2 is a top plan view of the equipment shown in Figure 1.

Figure 3 is a section on line 3—3 of Figure 1, showing the manner of mounting the supporting arm to permit of vertical swing and showing the manner of holding the supporting arm bracket at different points of its adjustment vertical of the supporting column.

Figure 4 is a section on line 4—4 of Figure 1, showing the manner of holding the supporting arm in different positions of its vertical swinging movement.

Generally speaking, the present drill comprises a motor designed to receive various drills interchangeably and which motor is slidably mounted upon a supporting arm so that it may be advanced to and from the face to be drilled. This arm is pivoted at one end to a bracket that in turn is adjustably connected to a supporting column, the connection of the arm with the bracket permitting its free end to be raised and lowered so as to correspondingly position the motor with its drill.

Referring to the drawings, the supporting column includes an upper rectangular bar 10, the lower end portion of which is threaded as shown at 11 and slidably disposed within a base 12. A hand wheel 13 rests upon the upper end of the base and engages the threads 11 so that by adjustment of this hand wheel, the bar 10 may be raised and lowered in the base, thus to firmly position the base against the floor of the tunnel or chamber, as the case may be and to correspondingly position the upper end of the bar against the roof. The base is provided with the projections illustrated, to prevent slipping.

Upon the bar 10 of a column is mounted a U-shaped bracket comprising the spaced legs 14 and 15 and the connecting bight portion 16, through which latter is formed a rectangular opening 17 that slidably receives the bar of the supporting column. Through the bracket at one side of the opening 17 is a threaded perforation 18 in which is engaged a set screw 19, designed to engage interchangeably the depressions 20 in the bar 10.

Through the legs 14 and 15, midway between the bight 16 and the free ends of the legs are formed registering openings 21 and 22 that receive a pivot bolt 23 that is engaged also through the disc 24 at one end of a supporting arm 25. The disc 24 is provided with an arcuate series of perforations 26, which series is concentric to the disc and extends the same angular distance both above and below the arm. It will be noted upon reference to Figure 1 of the drawings that the supporting bracket is of considerable vertical extent, which extent is equal approximately to the diameter of the disc 24 and through these legs of the bracket are formed the upper and lower perforations 27 and 28 respectively, either of which may receive a locking pin 29 passed also through a perforation 26. When the supporting arm is swung downwardly on its pivot bolt 23, the pin is operated in the lower perforation 28 and when the supporting arm is swung downwardly from horizontal position on its pivot bolt 23, the pin 29 is operated in the lower perforation 27 and when the arm is swung upwardly, the pin is operated in the upper perforation 27, as will be understood.

The arm 25 serves as a direct support for a motor base 30 having a rectangular passage 31 through it and in which is slidably

2
received the arm 25 that is rectangular in cross section and thus serves to permit of adjustment of the base longitudinally of it, while preventing its rotation on the arm.

5   Mounted upon the base 30 is a drill motor 32 held to the base by means of suitable straps 33. The rear end of the motor casting has a threaded extension 34, having threaded engagement with the eye 35 at one 10 end of a handle 36 provided with a grip 37 at its free end and through the medium of which the motor with the base may be slid forwardly and rearwardly along the supporting arm.

15   The motor shaft 38 is provided with a chuck 39, of any approved type, to permit of coupling of drills 40 quickly and interchangeably with a motor shaft.

With the present construction, it will be 20 understood that with the parts assembled in the manner described, the column is set up in the proper angular relation to the face to be drilled, after which the bracket is adjusted vertically of the column and held 25 at the desired point through the medium of the set screw 19. The supporting arm 25 is then swung on its pivot bolt 23 to adjust the motor with its drill in a vertical plane so that the drill will be presented to the 30 face of the work at the desired angle. The circuit of the motor being then closed, the drill is actuated and is pressed against the work by shoving on the handle grip 37. When the drilling has proceeded to the 35 proper depth, the motor with the drill is drawn rearwardly of the supporting arm and another drill is substituted, after which the motor is again shoved forwardly to carry the drill into the hole with a continuation of the drilling operation. This is 40 continued until the hole has been drilled

to the proper depth, after which the motor with the drill may be given any one of the various adjustments provided for so as to form the next hole in the proper position 45 and direction.

It will be noted that the structure illustrated permits of extreme lightness and durability and insures firmness of the drill and extreme ease of its operation.

It will be noted that at the free end of the arm 25 is a perforation in which is received a cotter pin 25' that prevents accidental movement of the motor base off from the arm. It will be noted, further, that by reason of the fact that the arm is square in cross-section and the passage through the motor base is of the same shape, the motor may be set above, below or at either side of the supporting arm.

60   What is claimed is:

A mine drill stand comprising the combination with a supporting column having a series of notches in one of its longer edges, and a platform for supporting a drill motor, of a housing having a vertical opening receiving the column therethrough and having a screw engageable in the said notches, the housing being bifurcated throughout the greater part of its length and formed with 65 transverse central aligned pivot openings for the pivot of the platform and a circular series of openings concentric with the pivot openings for the reception of a pin carried 70 by the housing and engageable through the 75 housing and platform.

In testimony whereof I affix my signature, in the presence of two witnesses.

GEORGE DOBSON.

Witnesses:

WALTER C. FAIRWEATHER,
NAVARRE WALKLEY.
